Nathaniel Waterman, of Boston, Mass.
Letters Patent No. 1046-dated Aug. 31, 1888.

The schedule referred to in these Letters Patent and making part of the same.

To all persons to whom these presents shall come:

Be it known that I, Nathaniel Waterman, of Boston, in the County of Suffolk, and State of Massachusetts, have invented a new and ornamental design for Biscuit or Bread Pans, and I do hereby declare that the same is duly represented in the accompanying drawings, of which,

Figure 1. is a top view.

Figure 2. a side elevation, and

Figure 3. a longitudinal section of the pans connected together and formed in accordance with the said design.

One of the said pans is represented as of an elliptical shape and as having the word "faith" raised in relief within it, and with the letters composing the same in reverse, so that when bread or dough may be baked in said pan, the word "faith" shall be stamped thereon.

The next pan is of an elongated shape, and has the word

ments, with the ornamented base piece G, and extension H, to which extension the side rail of the headstead is attached, and the head I, with its combination of spirally beaded edges and scroll & leaf work; all as set forth more clearly and particularly in the accompanying drawing

What I claim as my invention or production and desire to secure by letters patent is the arrangement and combination of figures, devices and ornamentation represented in the accompanying drawing, the whole forming an ornamental design for a cast iron Beadstead Leg.
